By # UNITED STATES PATENT OFFICE.

THEODORE L. PATRICK, OF PAWPAW, ILLINOIS.

WINDOW-SASH BALANCE.

1,420,280.

Specification of Letters Patent. Patented June 20, 1922.

Application filed March 11, 1921. Serial No. 451,437.

To all whom it may concern:

Be it known that I, THEODORE L. PATRICK, a citizen of the United States, residing at Pawpaw, in the county of Lee, State of Illinois, have invented certain new and useful Improvements in Window-Sash Balances; and I do hereby declare the following to be a full, clear, and exact description of the invention, such as will enable others skilled 10 in the art to which it appertains to make and use the same.

This invention relates to new and useful improvements in window sashes and particularly to sash weight means for sashes.

One object of the invention is to provide 15 a means for holding the sash cords of the weights from which the window sash can be easily and quickly disengaged, so that the window sash may be taken from the window frame.

Another object is to provide a sash weight means for a window whereby the usual parting beads and blind stops are done away with, the sash cord holding means serving 25 to maintain the sash in the frame.

Another object is to provide a sash cord holding means whereby when the cord is released from the sash, the end of the cord may again be easily reached and re-attached 30 to the sash.

Other objects and advantages will be apparent from the following description when taken in connection with the accompanying drawing.

35 In the drawing:

Figure 1 is an elevation of a window frame and sashes, showing the invention applied thereto.

Figure 2 is a horizontal transverse sectional view through one of the sashes and the frame, showing the cord holding means and its cooperation with the sash and frame.

Figure 3 is an enlarged front elevation of a portion of the frame, and one side of the 45 sash showing the cord end released from the sash.

Figure 4 is a vertical longitudinal sectional view through one side of the frame of the window and the adjacent side of the 50 sash, the cord holder being shown in elevation.

Ordinarily, with the common window sash, when it is desired to remove the sash from the window frame, it is necessary to 55 remove the stop, pry out or detach the end

of the sash cord which is secured to the sash, and then be very careful not to let go of the cord end, as a knot must be tied therein to prevent the same from being drawn into the stile pocket by the weight. This is 60 a very laborious method, and it is with the object of obviating this inconvenience that the present device was provided.

Referring particularly to the accompanying drawing, 10 represents one side of the 65 window frame in which is formed the stile pocket 11, for the sash weight 12, and to which latter is connected the sash cord 13. The cord passes out through the wall of the stile and is secured within the intermediate 70 portion of a metal tube 14. This tube, however, has approximately one-half of its width removed, longitudinally thereof to permit the sash cord to play in and out thereof, as shown at 15. In the opposite 75 side of the tube is formed an opening 16 in which is received the inner end of a spring pressed pin 17, disposed through the vertical side rail of the sash, the outer end of said pin being formed with a finger grip 80 18, which is adapted to be grasped to release the pin from the tube. In the face of the stile is formed a longitudinally extending groove 19 for the reception of the before-mentioned tube 14, and in which groove the 85 said tube slides, as the sash is raised and lowered. In the adjacent edge face of the sash is also formed a longitudinally extending groove 20 also receiving the tube 14, whereby, when the sash cord is properly 90 secured to the tube, and the spring pressed pin is within the opening 16, the sash will be held from movement out of the window frame, but is permitted to be moved upwardly and downwardly.

When it is desired to remove the sash from the window frame, the spring pressed pin 17 is pulled from the opening 16, when the sash weight will drop to the bottom of the pocket in the stile, and draw the tube 14 95 to the upper end of the window frame, out of the groove of the sash. In view of the fact that there is no stop in the window frame, the sash may be easily and quickly drawn out from the window frame, by a 100 movement straight outwardly toward the operator.

It will, of course, be understood that the sash weight, cord, and tube, are duplicated 105 on the other side of the window frame and

sash, as well as the spring pressed pin. Furthermore, the same means is used in connection with the upper sash, as that described in connection with the lower sash.

5 Thus the saving of a large amount of wood, in the making of window frames, is accomplished, and the removal of the sash rendered easy and without special tools, or any great amount of time and labor.

10 What is claimed is:

1. A window and sash construction comprising a frame having stile pockets and longitudinal grooves in the faces of said stiles, the sash having a longitudinal groove in each outer vertical edge face, a weight in each pocket and having a cord thereon extending outwardly through the wall of the stile pocket, and means detachably connected with the sash and permanently attached to the cords for holding the cords to the sash, said holding means being partly disposed in the groove of the sash and being partly disposed in the groove of the

stile for sliding movement therein as the sash is raised and lowered in the frame. 25

2. A window and sash construction including a stile pocket and sash weight including a sash cord, a sash having a longitudinal groove in each vertical edge face, each stile having a groove throughout its 30 length, a tubular member disposed partly in each sash groove and partly in a stile groove for slidable movement in the latter, one end of the sash cord being secured to the tubular member, and means on the sash 35 for releasably holding the tubular members in the grooves of the sash and serving to maintain the sash within the frame by their engagement in the said grooves.

In testimony whereof, I affix my signature, in the presence of two witnesses.

THEODORE L. PATRICK.
